UNITED STATES PATENT OFFICE.

HARRY V. HAIGHT, OF SHERBROOKE, QUEBEC, CANADA, ASSIGNOR TO INGERSOLL-RAND COMPANY, OF JERSEY CITY, NEW JERSEY, A CORPORATION OF NEW JERSEY.

FEEDING MECHANISM FOR ROCK DRILLS.

Application filed July 2, 1923. Serial No. 649,083.

To all whom it may concern:

Be it known that I, HARRY V. HAIGHT, a citizen of the Dominion of Canada, and a resident of Sherbrooke, Province of Quebec, Canada, have invented a certain Feeding Mechanism for Rock Drills, of which the following is a specification, accompanied by drawings.

This invention relates to rock drills but more particularly to the feeding means of a stope drill.

One of the main objects of the invention is to enable the packing in the feed piston of a stope drill to be automatically forced tightly against the feed cylinder in accordance with the pressure in the feed cylinder, so that the packing always remains tight.

Another object of the invention is to produce a piston having relatively movable parts, between which a packing is located, and adapted to be pressed against the feed cylinder in accordance with the pressure in the feed cylinder.

Further objects of the invention will hereinafter appear, and the invention is illustrated in one of its preferred forms in the drawings, in which

Figure 1 is a side elevation partly in vertical section of a stope drill, which has been selected as an example of a rock drill to which the invention may be applied.

Figure 2 is a fragmentary detail vertical sectional view of a modified form of the invention, and

Figure 3 is a similar view of a further modification of the invention.

Referring to the drawings, the stope drill has the cylinder A, to which is secured the front head B by the usual side bolts C and in which front head the drill steel D extends for receiving the impact blows of the hammer piston. The cylinder A is separated from the feed cylinder E by the head block F, to which is secured the usual rotation handle G for manually rotating the drill steel D. Motive fluid is admitted to the machine through the inlet H and is controlled by the usual throttle valve having a handle J.

In accordance with my invention, the feed piston K comprises the cylindrical cap piece L and a cup shaped hollow main head O. The cap L is adapted to have limited longitudinal movement in the main head O and the body portion of the cap is guided in the

cup shaped cavity by the walls of the head. The cup L is provided with a flange at its outer end which, with the head O and the walls of the cylinder A, forms an annular recess of rectangular section in a longitudinal plane. In the recess between the flange of the L and the main head O is located a packing P which may be of hemp, long fiber braided asbestos, or other suitable material. The main head O in this instance is formed with a hollow projecting end Q to which is secured, as by the rivet R, the usual feed piston rod S, carrying the usual rock engaging pointer T at its lower end. A guide bolt U is provided in this instance with an enlarged neck or portion U', forming a shoulder U² adapted to bear against the cap L. The head V of the bolt is rectangular and located in the projection Q and the shank of the bolt is passed through the main piston head O, cap L and the washer W, and is secured by the nut g so that the shoulder U² is drawn against the cap, and the cap and bolt are firmly held together. A spring X preferably in the form of a split ring, surrounds the washer W and is adapted to cooperate with the bushing Y for locking the piston and piston rod in its extreme inward position in the feed cylinder E. The head V of the bolt in Figure 1 has limited longitudinal movement between the rivet R and main head O, which forms stops for the bolt head V, and the bolt cannot turn.

As pressure fluid is admitted to the feed cylinder through the passage J', the cap L is forced downwardly, and presses the packing P tightly against the cylinder. The greater the pressure within the cylinder, the more tightly will the packing P be forced against the cylinder, thus preventing leakage of pressure fluid from the cylinder, so that the machine is held in the desired working position.

In the modification shown in Figure 2, the projection Q of the main head O is formed with the longitudinal grooves a and b and the enlarged portion or neck U' of the bolt U is provided with a rivet c, having an enlarged head e. In the assembly of the parts, the enlarged rivet head e is first moved downwardly in the groove a until it passes the end of the projection Q, and is then turned and moved upwardly in the second groove b, which only extends a short distance in the main head O. A rivet f is then in-

5 serted to hold the piston rod S and the washer W of the main head O together, and also to serve the additional purpose of preventing the bolt U from dropping out, 10 should its nut g become loose.

In the modification shown in Figure 3, the feed piston rod S' is formed with an integral main head h having a groove j, through which the enlarged head k of the rivet o may be passed and then turned about and moved up within the main head, as shown. A stop member p is secured to the piston rod S and prevents the bolt U from falling out.

15 I claim:

1. A fluid pressure piston, comprising a cup shaped main hollow piston head, a cylindrical cap having limited longitudinal movement in said hollow head, the body portion of said cap being guided in the head cavity by the walls of the head, said cap having a flange at its outer end, packing material in the recess formed between the said cap flange and the main head, a guide bolt having an enlarged neck forming a shoulder, a bolt shank passing through the said cap, and means for rigidly securing the bolt in the cap, the neck of the bolt extending inwardly into the main piston head, 20 stops on the main piston head, a stop on the bolt neck cooperating with said stops on the main piston head for limiting the longitudinal movement of the bolt and cap relatively to the main piston head.

2. A fluid pressure piston, comprising a cup shaped main hollow piston head, a cylindrical cap having limited longitudinal movement in said hollow head, the body portion of said cap being guided in the head cavity by the walls of the head, said cap having a flange at its outer end, packing material in the recess formed between the said cap flange and the main head, a guide bolt rigidly secured in the cap and having an enlarged portion extending inwardly into the main piston head, stops cooperating with said enlarged portion of the bolt for limiting the longitudinal movement of the bolt and cap relatively to the main piston head, 25 and means for preventing the bolt from turning on its own axis.

3. A fluid pressure piston, comprising a cup shaped main hollow piston head, a cy-

lindrical cap having limited longitudinal movement in said hollow head, the body portion of said cap being guided in the head cavity by the walls of the head, said cap having a flange at its outer end, packing material in the recess formed between the said cap flange and the main head, a guide bolt having an enlarged neck forming a shoulder, a bolt shank passing through the said cap, and means for rigidly securing the bolt in the cap, the neck of the bolt extending inwardly into the main piston head, 30 stops on the main piston head, a stop on the bolt neck cooperating with said stops on the main piston head for limiting the longitudinal movement of the bolt and cap relatively to the main piston head, and means 35 also cooperating with the stop on the bolt neck for preventing the bolt from turning on its own axis.

4. A fluid pressure piston, comprising a cup shaped main hollow piston head, a cylindrical cap having limited longitudinal movement in said hollow head, the body portion of said cap being guided in the head cavity by the walls of the head, said cap having a flange at its outer end, packing material in the recess formed between the said cap flange and the main head, a guide forming a part of the cap and extending inwardly from the body portion of said cap into the main piston head, and stops cooperating with said guide for limiting the longitudinal movement of the guide and cap relatively to the main piston head.

5. A piston for use in fluid pressure feeding mechanism for rock drills adapted to slide within a feed cylinder comprising, a main head, having a hollow projecting end, a cap, packing material between said cap and said head, a bolt extending through said cap into said hollow end, a groove extending the length of said hollow projecting end and a second shorter groove whereby the bolt is adapted to be inserted through the first said groove and turned and held in the second shorter groove, and means for limiting the longitudinal movement of said cap and bolt with respect to said main head.

In testimony whereof I have signed this specification.

HARRY V. HAIGHT.
